ABSTRACT OF THE DISCLOSURE

A ball tether cord comprises two cord sections each having one end connected to one end of the other, the other ends of said sections being connected respectively to a ball and to a tethering pin, one of said sections being longitudinally resilient or elastic and the other being relatively non-stretchable, and a non-stretchable check cord is connected to said tethering pin and to said non-stretchable section beyond the ends of the elastic section, to positively limit the extent of stretch of said elastic section, said check cord and said non-stretchable section of the tether cord comprising in some cases integral portions of one piece of cord.

This application is a continuation of my application filed May 11, 1967, Ser. No. 637,749.

BACKGROUND OF THE INVENTION

There are several forms of ball game devices, particularly for golf practice, which include means intended to return the ball to the player after the ball has been struck.

In one device, a non-stretchable cord has its ends connected respectively to a ball and to a pin or stake to be driven into the ground, but this device is not satisfactory because unless the ball is struck in a special way it will not return to the player.

In another device shown in Patent No. 1,326,976, a length of non-stretchable cord is connected at one end to one end of an elastic cord and the other ends of the cords are connected respectively to the ball and the stake, but this device leaves much to be desired because the elastic cord is repeatedly stretched to its limit by the struck ball so as to be short-lived, and there is the possibility of the player being hit by the ball during its forceful return upon contraction of the elastic cord.

Another device is shown by Patent No. 2,032,081; the ball is attached to one end of a non-stretchable cord the other end of which is connected to a stake, and an elastic cord is connected to and arranged transversely of the non-stretchable cord with its ends anchored to the ground. While the elastic cord will return the ball, the cord tends to break down quickly and the ball must be struck by a wood, or iron driver to cause the ball to follow a low trajectory or the ball will not be returned to the hitter; it will drop to the ground near the stake far short of the tee.

SUMMARY

An object of the present invention is to overcome the disadvantages and weaknesses of the known devices described above, and to provide a game device wherein the tether cord shall include both an elastic or resilient cord section and a non-elastic or non-stretchable cord section and there shall be novel and improved means for controlling the stretchable of the elastic section in such a way as to ensure the return of the struck ball to the player and with a minimum of danger of

2

the ball striking the player. The invention particularly contemplates an additional non-stretchable check cord connected to the tethering pin and to non-stretchable portions of the tether cord beyond the ends of the elastic section to limit the stretching of the elastic section.

A BRIEF DESCRIPTION OF THE DRAWINGS

FIGURE 1 is a plan view of the ball game device embodying the invention with the parts in normal unstretched condition;

FIGURE 2 is a greatly enlarged plan view of the parts shown in FIGURE 1 with portions broken away and with the connections of the various sections of the tether cord shown in detail;

FIGURE 3 is a fragmentary sectional view approximately on the plane of the line 3—3 of FIGURE 2;

FIGURE 4 is a schematic side elevational view illustrating the ball near the end of its flight in solid lines and showing the device with the ball on the tee in heavy broken lines and the path of flight of the ball in light broken lines;

FIGURE 5 is a diagrammatic view illustrating the relative lengths of the sections of the tether cord.

**DESCRIPTION OF THE PREFERRED
EMBODIMENTS**

Specifically describing the embodiment of the invention shown in FIGURES 1 through 5, inclusive, the device includes a tether cord A comprising a longitudinally resilient or elastic section 1 at one end of which is connected as by a loop 2 and a knot 3 to one end of a non-stretchable section 4, the other ends of the sections 1 and 4 being shown as connected to a tethering pin 5 and to a ball 6. A non-stretchable check cord 7 has one end connected to the tethering pin 5 as indicated at 8 and its other end connected to the non-stretchable section 4 as indicated at 9.

As best shown in FIGURE 1, the length of the check cord 7 is substantially greater than the length of the completely contracted resilient section 1 and is substantially less than the length of the resilient section when the latter is stretched to its limit.

Preferably the non-stretchable section 4 and the check cord 7 comprise one piece that has one end connected to the tether pin, an intermediate portion looped around a fastener element such as a staple 10 in the ball 6 and returned upon itself providing parallel reaches 4a and 4b. Said reaches have looped connection 2 with the resilient section and are of equal length between the elastic section and the ball, and the end of the continuous cord opposite that connected to the tether pin is fast connected to the parallel reaches as indicated at 9.

When the device is in use, the tethering pin 5 is driven into the ground and a golf tee B is set in the ground at a distance from the tethering pin slightly less than the length of the tether cord A when the elastic section is completely contracted, as illustrated in heavy broken lines in FIGURE 4. When the ball is struck by a golf club in the hands of a player, the ball takes flight along a path generally indicated by the light broken line in FIGURE 4. The elastic section is stretched but the check cord limits the extent of the stretching to less than the stretching limit of the elastic section and at the same time stops the storage of energy in the elastic section while permitting absorption of the force incident to the flight of the ball and then automatic return of the ball to the player near the tee position without stretching or backlash of the elastic section by the momentum of the ball after the return of the ball to the tether pin. The force applied to the ball by the player's club is partially dissipated first in the stretch of the elastic section until that stretch is stopped by the check cord which thereby stops the storage

of energy in the elastic section and also independently of the elastic cord section positively stops the flight of the ball so that the force of the ball in flight is transmitted solely through the non-stretchable section and the check cord to the tether pin and the stored energy in the elastic section returns the ball approximately to the tether pin from where the ball rolls or hops to approximately the tee position.

It has been found from experience that the elastic or stretchable section of the tether cord has a life many times longer than the life of the elastic section of the device shown in Patent No. 1,326,976. Furthermore, the device of the invention is adaptable to use with any golf club from a driver to a wedge and will return the ball to the starting position because of the short distance required for use of the device (approximately 18 to 20 ft.). This is in contrast to the known devices which require the use of particular golf clubs and the striking of the ball in a particular manner, as well as distances of from 27 to 40 ft. Another important advantage of the device of the invention is that the stretch of the elastic section when the ball is struck by the player is limited and the elastic section does not stretch during the return of the ball which is believed to be due in part to the dissipation through the check cord of the force produced by the ball in flight into the ground at the tethering pin and to the limitation of the storage of energy in the elastic section during the flight of the ball.

While the relative lengths of the portions of the tether cord and check cord may be varied according to conditions of use, it has been found that a resilient section of about 54" in length, a non-stretchable section about 36" in length and a check cord of about 90" in length, produce satisfactory results. The length of the check cord between the points of connection to the non-stretchable portions beyond opposite ends of the resilient section will of course vary with the length of the resilient section and the degree of elasticity thereof. In the present instance the length of the check cord is in the order of one and two-thirds times the length of the completely retracted resilient section and the resilient section is stretchable to a length that is substantially greater than one and two-thirds times its completely contracted length.

While different types of cord may be utilized for the non-stretchable section and the check cord, it is desirable that a known type of braided nylon cord be used; and the form of the resilient section may be varied, but preferably is a known type comprising a nylon covered group of rubber strands.

The important features of the invention are:

(a) one end of the elastic cord section is connected directly to the tethering pin, and one end of the non-stretchable check cord is connected directly to the tethering pin independently of the elastic section, while the other end of the check cord is connected to the non-stretchable section 4 of the tether cord between the elastic cord section and the ball as clearly illustrated in FIGURES 1 and 2 of the application drawings,

(b) the relative lengths of the elastic cord section and the check cord provides independently of the elastic cord section a positive stop to the flight of the ball when the ball is driven by a club in a natural line of flight from a tee position across the tethering pin, and the elastic cord section is entirely relieved of the shock incident to the stoppage of the ball,

(c) at the same time check cord provides a positive limitation to the extent of stretch of the elastic cord to ensure a minimum of strain, wear and tear on the cord,

(d) which limitation to the extent of stretch also constitutes a limitation to the storage of energy in the elastic cord section incident to the flight of the ball, and

(e) the elastic cord section is light because the force applied to the struck ball is completely assumed by the strong check cord and the tether pin, and the elastic cord has relatively small elasticity, so that the small amount of energy stored in the elastic cord section is just sufficient to cause a return of the ball to a point near the tether pin, and the residual small momentum of the ball causes the ball to automatically roll or hop to the tee position and eliminates the danger that the player might be struck by the ball as a result of backlash upon contraction of the elastic cord without danger of the player being struck.

What is claimed is:

1. A golf game practice device including a ball adapted to be driven into a natural line of flight by a golf club, a tethering pin adapted to be secured in the ground and a tether cord connected at its ends to said ball and to said tethering pin respectively, said tether cord including an elastic cord section and a relatively short non-stretchable cord section, and a non-stretchable check cord, said elastic cord section having one end thereof secured to the tethering pin in direct engaging relationship therewith and its other end connected to one end of said non-stretchable cord section, the other end of said non-stretchable cord section being connected to the ball, said check cord having one end thereof secured to said tethering pin in direct engaging relationship therewith independently of said elastic cord section and its other end secured to said non-stretchable cord section in direct engaging relationship therewith between said elastic cord section and the ball, said check cord having a length substantially greater than the length of the completely contracted elastic cord section and the length of the check cord being less than the length of the elastic cord section when the latter is stretched to the limit, thereby providing independently of said elastic cord section a positive stop to the flight of the ball when the ball is driven by a club in a natural line of flight from a tee position across the tethering pin and at the same time providing positive limitation to the extent of stretch of said elastic cord section and the storage in the elastic cord section of energy by which the ball is automatically returned to approximately the tethering pin upon contraction of said elastic cord section and thereafter is caused to roll and hop on the ground approximately to the tee position.

2. A game device as defined in claim 1 wherein the length of the check cord is of the order of one and two-thirds times the length of the completely contracted elastic section, and the elastic section is stretchable to a length which is greater than one and two-thirds times its completely contracted length.
